COAL MINING MACHINE

Merlin R. Stevenson, Craig, Colo.

Application October 25, 1948, Serial No. 56,450

5 Claims. (Cl. 262—9)

1

This invention relates to a method of, and apparatus for, mining coal or similar materials, and more particularly to a boring head for boring into a wall of coal.

The principal object of the invention is to provide a boring head which will simultaneously cut and break the coal from the vein ready for haulage.

Another object is to so construct the device that it can be applied to present rail supported, coal cutting machines; and so that it can be operated at any desired height or at any desired angle so as to obtain full advantage of the position of the coal.

Another object of the invention is to provide a method of mining coal wherein relatively large, round bores are made into the coal at spaced intervals so that the intervening coal between the bores can be readily broken down.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawings:

Fig. 1 is a side elevation, illustrating the invention applied to a typical "Universal" coal cutter, such as used in coal mines;

Fig. 2 is a front view of the improved boring head, looking in the direction of the arrow "2" in Fig. 1;

Fig. 3 is an enlarged, longitudinal section through the boring head, taken on the line 3—3, Fig. 2;

Fig. 4 is a still further enlarged, detail, horizontal section, taken on the line 4—4, Fig. 3; and

Fig. 5 is a similarly enlarged top view of the improved boring head, looking in the direction of arrow "5" in Fig. 3.

In Fig. 1 a typical universal coal cutter is illustrated, of the type known in the art as the "Jeffrey 29-U." Coal cutters of this type are mounted on a truck 10 supporting a turntable 11 and a motor and reel box 12. A boom 13 is mounted on a horizontal hinge 14 on the turntable 11 so that it may be raised and lowered through the medium of hydraulic jacks 15.

The boom 13 is provided with hydraulic motors for rotating a cutter bar and for rotating a tubular housing about the cutter bar. The cutter bar

2

in the usual coal cutter operates an elongated, flat cutter head for shearing or cutting slots in the coal. In applying this invention, the usual cutter head with its cutter bar and sleeve are removed and the improved boring head is applied in their stead.

The improved boring head is provided with a tubular supporting shaft 16 which replaces the sleeve of the usual cutter head, and which is rotated by the mechanism in the boom 13 which rotates the sleeve of the usual head. A central shaft 17 passes through the tubular shaft 16 and replaces the usual cutter bar of the conventional coal cutter.

15 The hydraulic motors in the boom 13 rotate the tubular shaft 16 and the shaft 17 under the same controls and by means of the same mechanism that formerly operated the cutting chain and boring bar of the usual coal cutter.

20 This invention relates more particularly to the cutting or boring head of the device. This head comprises a shaft housing 18 provided at its one extremity with a 90° peripheral flange 19 and at its other extremity with an inclined attachment flange 20.

25 The tubular shaft 16 is provided at its outer extremity with an inclined flange 21 against which the flange 19 is bolted by means of suitable cap screws or bolts 22. This arrangement positions the axes of the housing 18 and the shaft 16 so that they will intersect each other at an angle of approximately 10°, as shown in Fig. 3.

30 A stub shaft 23 is rotatably mounted in suitable anti-friction bearings 24 in the housing 18. The stub shaft carries a driven bevel gear 25 at its inner extremity, which is in constant mesh with a drive bevel gear 26 on the extremity of the shaft 17. The shaft 17 is rotatably and axially mounted in the tubular shaft 16 in suitable anti-friction bearings 27.

35 A breaking blade 28 is mounted on the forward flange 20 of the housing 18 by means of cap screws 29. The outer edge of the breaking blade swings spirally rearward, similarly to the blade of an auger or boring bit.

40 A coal cutting chain 30 is positioned at the entering edge of the breaking blade 28 so as to cut a slot for the blade to enter. The cutting chain is any of the usual standard coal cutting chains, provided with cutting teeth 31 for cutting a channel in the coal. The chain 30 is endless and is trained round a chain sprocket 32 and round an arcuate tension block 33.

45 A separating block 34 is positioned between the sprocket 32 and the block 33. A tension screw

35 is threaded into the block 34 and bears at its outer extremity against the block 33 so that the block 33 can be forced outwardly to increase the tension in the chain 30.

The tension screw 35 is provided with a wrench portion 41 which is accessible through an opening 42 in the plate 36.

The block 34 is rigidly mounted between an outside chain-retaining plate 36 and an inside chain-retaining plate 37. The plates 36 and 37 are elongated and provided with rounded extremities to conform to the path of, and to slidably support, the chain 30. The plates are rigidly attached in place by means of attachment screws 38 which pass the outer plate 36, and are threaded into the breaking blade 28.

The block 33 is adjustably supported between the plates 36 and 37 by means of clamp screws 39 which pass through the outer plate 36 and through elongated slots 40 in the block 33, thence through the inner plate 37 and are threaded into the breaking blade 28. The elongated slots 40 serve to allow outward and inward movement of the block 33 under the influence of the screw 35.

It can be readily seen that as the tubular shaft 16 is rotated by the hydraulic motors in the boom 13, the axis of the housing 18 will gyrate in a conical path, carrying the breaking blade forwardly in the direction of the arrow in Fig. 2.

It will be noted that, due to the incline of the blade 28 and to the incline of the shaft 23, the entering edge of the blade 28 will be positioned well forward of the trailing edge thereof. The entering edge carries the coal-cutting chain 30, and this chain is rotating at higher speed than the tubular shaft 16, since the construction of the conventional coal cutter rotates the shaft 14 at higher speed.

Thus, it will be seen that the teeth 31 will cut a channel in the coal and, as the entering edge rotates, the entering edge of the blade 28 will enter this channel, and the rearward incline of the blade 28 will break the coal from the channel outwardly so as to rapidly bore a hole on a relatively steep helix while simultaneously breaking the coal backwardly between the cuts of the helix.

The entire coal face can be rapidly removed by a simple boring operation, or the face may be bored at spaced-apart points in the face, and the coal between the bores may be broken down.

The construction of the coal cutter illustrated in Fig. 1 allows the boring head to be raised and lowered from the floor to a height to cut eight feet above the floor, and the boom 13 may be swung from side to side to cover a width of fifteen feet. The breaking blade 28 is advanced into the coal face by the natural incline of the breaking blade and by the self-propelling of the truck 10 forwardly. The boring head may be made in any size. As illustrated, it is designed to bore a hole in the coal approximately four feet in diameter.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A boring head for coal cutting machines comprising: a shaft housing; a stub shaft rotatably mounted in said shaft housing; a spirally inclined breaking blade fixedly mounted on the forward face of said housing the outer edge of said

blade extending spirally rearward; an endless coal cutting chain positioned at the entering edge of said blade so as to cut a slot for the blade to enter; a tubular shaft connected to and supporting said housing; and a chain sprocket on said stub shaft supporting said chain.

2. A boring head for coal cutting machines comprising: a shaft housing; a stub shaft rotatably mounted in said shaft housing; a spirally inclined breaking blade fixedly mounted on the forward face of said housing the outer edge of said blade extending spirally rearward; an endless coal cutting chain positioned at the entering edge of said blade so as to cut a slot for the blade to enter; a chain sprocket on said stub shaft supporting said chain; a tubular shaft connected to and supporting said housing; so as to position the stub shaft so that its axis will intersect the axis of said tubular shaft at an acute angle; an axial drive shaft in said tubular shaft and driving said stub shaft; and means for rotating said tubular shaft and said central shaft independently of each other.

3. A boring head for coal cutting machines comprising: a shaft housing; a stub shaft rotatably mounted in said shaft housing; a spirally inclined breaking blade fixedly mounted on the forward face of said housing the outer edge of said blade extending spirally rearward; an endless coal cutting chain positioned at the entering edge of said blade so as to cut a slot for the blade to enter; a chain sprocket on said stub shaft supporting said chain; a tubular shaft connected to and supporting said housing so as to position the stub shaft so that its axis will intersect the axis of said tubular shaft at an acute angle; an axial drive shaft in said tubular shaft; bevel gears connecting said drive shaft to said stub shaft; and means for independently rotating said drive shaft and said tubular shaft in the same direction and at differing speeds.

4. A coal cutting device comprising: a tubular shaft; an axial shaft passing axially through said tubular shaft; means hingedly supporting one extremity of said tubular shaft; means for swinging the other extremity of said tubular shaft about said hinge means; a head member secured to the free extremity of said tubular shaft; a breaking blade mounted on said head member the outer edge of said blade extending spirally rearward; a sprocket shaft in said head member; a sprocket on the forward extremity of said sprocket shaft; an endless coal cutting chain trained about said sprocket and positioned at the entering edge of said breaking blade to cut a path for the latter; and means for rotating said tubular shaft and said axial shaft at different speeds in a common direction, the axis of said sprocket shaft intersecting the axis of said axial shaft at an angle of approximately 10°; and means transmitting the rotation of said axial shaft to said sprocket shaft.

5. A coal cutting device comprising: a tubular shaft; an axial shaft passing axially through said tubular shaft; means hingedly supporting one extremity of said tubular shaft; means for swinging the other extremity of said tubular shaft about said hinge means; an inclined flange at the free extremity of said tubular shaft; a head housing secured on said inclined flange so as to position its axis at an angle to the axis of said tubular shaft; an inclined attachment flange at the forward face of said housing; a breaking blade secured on the forward face of said attachment flange; an inside chain retaining plate secured

against said breaking blade; a stub shaft extending through said breaking blade and said retaining plate; a chain sprocket mounted on the forward extremity of said stub shaft; a separating block positioned adjacent said sprocket; an arcuate tension block positioned alongside said separating block; an endless coal cutting chain trained around said sprocket and said tension block; means for separating said tension block from said separating block to increase the tension in said chain; an outer chain retaining plate covering said sprocket and said blocks; means transmitting rotation from said axial shaft to said stub shaft; and means for rotating said tubular shaft and said axial shaft, said cutting chain being positioned at the entering edge of said breaking blade so as to cut a slot for said blade to enter,

the outer edge of said blade extending spirally rearward so as to break the coal rearward from said slot.
